UNITED STATES PATENT OFFICE.

ADAM HAAR, OF SAGINAW, MICHIGAN.

DESIGN FOR A WEATHER VANE.

Application filed October 14, 1922. Serial No. 3,979. Term of patent 14 years.

To all whom it may concern:

Be it known that I, ADAM HAAR, a citizen of Russia, residing at Saginaw, in the county of Saginaw and State of Michigan, have invented a new, original, and ornamental Design for Weather Vanes, of which the following is a specification, reference being had to the accompanying drawing, forming part thereof, and in which—

I claim:

The ornamental design for a weather vane, as shown.

ADAM HAAR.
